UNITED STATES PATENT OFFICE.

HENRY MILLER, OF BROOKLYN, NEW YORK.

CIGAR ADVERTISING AND LIGHTING DEVICE.

973,372.

Specification of Letters Patent. Patented Oct. 18, 1910.

Application filed June 30, 1909. Serial No. 505,137.

To all whom it may concern:

Be it known that I, HENRY MILLER, a citizen of the United States, and residing at Brooklyn, in the county of Kings and State of New York, have invented certain new and useful Improvements in Cigar Advertising and Lighting Devices, of which the following is a specification, such as will enable those skilled in the art to which it appertains to make and use the same.

This invention relates to devices for advertising and lighting cigars; and the object thereof is to provide an improved device of this class which may be placed on a desk, counter or any other suitable support, and which is simple in construction and operation, and which may also be made to serve as a cigar cutter; and with this and other objects in view the invention consists in a device of the class specified constructed as hereinafter described and claimed.

The invention is fully disclosed in the following specification, of which the accompanying drawing forms a part, in which the separate parts of my improvement are designated by suitable reference characters in each of the views, and in which;

Figure 1 is a plan view of my improved cigar advertising and lighting device, Fig. 2 a central transverse vertical section, Fig. 3 a transverse vertical section approximately on the line 3—3 of Fig. 1, Fig. 4 a front or plan view of a rotatable cylinder which forms a part of the device, Fig. 5 a front view of the device complete, Fig. 6 an end view thereof, and Fig. 7 a plain view of an electric heating device which I employ.

In the practice of my invention, I provide a box or case *a* comprising a bottom member *a*², back member *a*³ and end members *a*⁴ and *a*⁵, and hinged at the front of the bottom member *a*² at *a*⁶ is a combined front and top cover member *a*⁷ having attaching lugs *a*⁸ by means of which it may be secured to the back *a*³ by screws as shown, but the particular form and construction of the box or case *a* forms no part of my invention, and said box or case may have any preferred and suitable shape and form or construction.

Secured to the inner face of the end member *a*⁵ is a stationary pivot shaft *b*, and secured to the inner face of the end member *a*⁴ is a hollow pivot block *b*², and mounted between the pivot shaft *b* and the pivot block *b*² is a drum *c* comprising heads *c*²

connected by parallel bars *c*³, and the drum *c* is adapted to rotate upon the pivot shaft *b* and pivot block *b*² by means of suitable bearings in the centers of the drum heads *c*² as clearly shown in Fig. 1. Upon the inner end of the pivot block *b*² is mounted an electric incandescent lamp *c*⁴, and between the base *c*⁵ of the lamp *c*⁴ and the corresponding head *c*² of the drum *c* is a ring *c*⁶ which together with a shoulder on the pivot block *b*² prevents longitudinal motion of the drum *c*.

Mounted loosely upon the pivot shaft *b* is a ratchet arm *d* having a long arm member *d*² terminating in a weight *d*³ and a short arm member *d*⁴ arranged to form a right angle as shown in Fig. 1 and terminating in a pin *d*⁵; and the pin *d*⁵ operates in a slot *d*⁶ carried in the upper end of a solenoid plunger *d*⁷ as plainly shown in Fig. 3, and the solenoid plunger *d*⁷ works vertically in a vertical solenoid *d*⁸, and the long arm *d*² of the ratchet arm *d* carries a pawl *d*⁹ pivoted at *d*¹⁰ to the arm *d*², and the pawl *d*⁹ engages the teeth of a ratchet wheel *d*¹¹ secured to the outer face of one of the drum heads *c*² of the drum *c* as shown in Fig. 3, and a tension spring *d*¹² secured to the ratchet arm *d* and the pawl *d*⁹ holds the pawl in engagement with the ratchet wheel *d*¹¹.

Mounted on the inner face of the end member *a*⁴ of the box *a* by means of a screw *e* is a cigar cutting device *e*² having a blade member *e*³ which lies flat against the inner face of the end *a*⁴ of the box and extends outwardly through the front *a*⁷ of the box through a suitable slot *e*⁴ terminating in a thumb handle *e*⁵, and the blade member *e*³ is normally held upwardly by a tension spring *e*⁶ as shown in Fig. 2 and is adapted to operate in connection with an aperture *e*⁷ in the end *a*⁴ of the box to cut off the end of a cigar when the latter is inserted into the aperture *e*⁷ as will be understood.

Mounted approximately centrally of the front *a*⁷ of the box is a cigar lighting device *f* comprising a main outer casing *f*² having an outwardly directed mouth *f*³ closed at the back by a perforated plate *f*⁴, and mounted within the main casing *f*² immediately behind the plate *f*⁴ is an electric heating device *f*⁵ shown in side elevation in Fig. 2 and in plan in Fig. 7, and comprising a base plate *f*⁶ preferably made of lava, and a coil or coils of fine conducting wire *f*⁷ mounted

thereon; and the lava base plate f^6 and the perforated plate f^4 are parallel and the coil or coils f^7 lie between the lava base plate f^6 and the perforated plate f^4 , and the terminal wires of the coil or coils f^7 pass backwardly through the lava plate f^6 and downwardly through a tubular extension f^8 of the main casing f^2 , and the form of construction of the main casing f^6 of the cigar lighting device f and the parts therein may be varied as desired, and my invention is not limited to the particular form shown.

In the operation of the cigar lighting device f , the end of a cigar is placed in the mouth f^3 and against the perforated plate f^4 and electric current passing through the coil or coils f^7 creates heat which ignites the end of the cigar.

20 In the bottom of the box a and adjacent to the end member a^5 and front a^7 thereof is a switch device g comprising a hollow support g^2 having a horizontal member g^3 on which is mounted a switch arm g^4 pivoted at g^5 and operating in connection with a contact block g^6 and normally held open as shown in Fig. 1 by a tension spring g^7 , and the switch arm g^4 carries a pusher g^8 pivoted at g^9 and passing forwardly through the front a^7 of the box through a suitable aperture g^{10} , and when the pusher g^8 is pushed inwardly from without by the thumb or otherwise the arm g^4 contacts with the contact block g^6 and an electric connection is made between the block g^6 and the pivot point g^5 as will be understood.

The back a^3 of the box a is provided with an aperture and insulating bushing h therein through which electric circuit wires h^2 are adapted to pass into the box, and the circuit wires h^2 are preferably connected at the outside of the box to an attaching plug h^3 , and after passing into the box one of the circuit wires h^4 goes to the solenoid d^8 and from there by a wire h^5 to the contact block g^6 of the switch, and the other circuit wire h^6 goes to the lamp c^4 by way of the hollow pivot block b^2 as plainly shown in Fig. 1, and from there by a wire h^7 into the tubular extension f^8 of the cigar lighting device f into and through the coil or coils f^7 therein and out from the cigar lighting device f to the blade g^4 of the switch g by way of a wire h^8 , and in this way it will be seen that the solenoid d^8 and lamp c^4 and cigar lighting device f and switch g are all in series and that by closing the switch g the three devices just mentioned will be supplied with an electric current.

The bars c^3 of the drum c are provided with supplemental bars c^7 of the same size and shape as the bars c^3 , and secured thereon by screws c^8 , and each pair of bars c^3 and c^7 thus forms a longitudinal clamping device c^9 , and each adjacent pair of clamping devices c^9 is adapted to receive and hold a

card c^{10} , and the card c^{10} closes up the openings between the bars and completely encloses the lamp c^4 , and the cards c^{10} are preferably made of transparent or translucent material, such as celluloid or thin card board, and are each preferably provided with a sign, an advertisement or like subject matter, and it will be seen that when the lamp c^4 is energized and the interior of the drum illuminated, the sign or advertisement on the cards c^{10} will stand out clearly to view. 70 75

In the form of construction shown, the combination front and top member a^7 of the box is provided with a sloping section a^9 80 which is provided with a longitudinal opening a^{10} closed by a plate of glass a^{11} and surrounded by a suitable frame or bead a^{12} ; and the general appearance of the window thus formed is shown at a^{13} in Fig. 5. 85

The operation of my invention will be readily understood from the foregoing description when taken in connection with the accompanying drawing and the following statement thereof. With the parts in their normal positions, the switch g is open and consequently the lamp c^4 , solenoid d^8 and cigar lighting device f are not actuated and the ratchet arm d occupies the position shown in Fig. 3 due to the gravity action of the weight d^3 and the plunger d^7 is at the upper end of its stroke as shown. When the operator uses the machine, he first inserts the end of his cigar in the aperture e^7 in the end a^4 of the box and depresses the blade member e^3 of the cutting device e by means of the thumb handle e^5 and thereby cuts off the end of the cigar. The operator then inserts the end of his cigar in the cigar lighting device as above described and presses the 90 95 100 105

pusher g^8 and as above described the latter operation will close the switch g and actuate the lighter f and at the same time the lamp c^4 and the solenoid d^8 , and as the coil or coils f^7 are being heated and are igniting the cigar, the solenoid d^8 will pull downwardly on the plunger g^7 and will rotate the ratchet arm d and the pawl with it around the longitudinal axis of the drum c and the pawl d^9 will engage and carry with it the ratchet d^{11} and the drum c , and one of the cards bearing an advertisement or sign will be brought immediately under and parallel with the window a^3 and the lamp c^4 will brilliantly illuminate said sign and it will be seen by the operator through the window a^{13} and command his attention. When the cigar has been ignited and the operator releases the pressure on the pusher g^8 the switch g is opened and the apparatus again made inoperative and the lamp c^4 goes out, and the solenoid plunger d^7 returns to the position shown in Fig. 3. 125

It will be understood that my invention is not limited to the particular form of mech- 130

anism shown for operating the drum step by step, nor to the form of drum, switch or cigar cutter as shown, and various changes in the forms of construction shown, and 5 changes in the arrangement of the parts of my apparatus may be made, within the scope of the appended claim, without departing from the spirit of my invention or sacrificing its advantage, and while I have shown 10 the electric devices to be all connected in series, it will be understood that a system of parallel connections or series parallel as desired may be used.

Having fully described my invention, 15 what I claim as new and desire to secure by Letters Patent, is:—

An apparatus of the class described, comprising a main frame or casing provided at one end with a pivot block and at the other 20 end with a pivot shaft, a rotatable drum mounted between said block and shaft, an electric lamp placed in said drum and connected with the inner end of said block, a ratchet arm mounted loosely on the pivot

shaft and having a short end and a longer 25 end provided with a weight, a solenoid in the lamp circuit and mounted adjacent to the pivot shaft and provided with a plunger having a slot, a pin connected with the shorter end of said arm and passing through 30 said slot, a ratchet connected with the adjacent end of the drum, a pawl connected with the longer end of said arm and operating in connection with said ratchet, a spring for moving said pawl in one direction, and 35 a pusher passing through the front of the frame or casing and by means of which the solenoid and lamp circuit may be closed and opened.

In testimony that I claim the foregoing as 40 my invention I have signed my name in presence of the subscribing witnesses this 28th day of June 1909.

HENRY MILLER.
